WICK TYPE OIL BURNER CONSTRUCTION

Carroll M. Breed, Ypsilanti, Mich., assignor to
United Stove Company, Ypsilanti, Mich., a cor-
poration of Michigan

Application April 3, 1939, Serial No. 265,811

10 Claims. (Cl. 67—68)

This invention relates generally to oil burners and refers more particularly to improvements in oil burners of the wick type.

It is one of the principal objects of this invention to provide a burner of the above type with a flame spreader capable of being assembled with the burner in a position inverted from its normal operating position on the burner and effective in the inverted position thereof to loosen or break the carbon deposit on the end of the wick.

Another advantageous feature of the present invention consists in the provision of a flame spreader rotatably supported on the burner in its inverted position and having a flame spreader flange provided with circumferentially spaced serrations engageable with the adjacent end of the wick in a manner to break or loosen the carbon deposit on the end of the wick without cutting or unraveling the wick.

Still another object of this invention resides in the provision of a flame spreader flange having an annular upwardly projecting downwardly opening channel portion effective in the inverted position of the flame spreader to telescope in the upper end of the wick tube and center the flame spreader relative to the wick.

A further feature of this invention resides in the provision of a flame spreader of the type set forth in the preceding paragraph wherein the channel collects air passing upwardly through the inner wick tube and is formed with apertures in the base portion thereof to permit the air to escape from the channel into the air discharged laterally from the flame spreader body above the channel. It has been found in actual practice that the above feature appreciably reduces the accumulation of unburned oil on the inner surface of the wick tube, and this is possibly due to the fact that the draft passing upwardly through the inverted channel on the flame spreader flange carries the unburned oil vapors along with it. Inasmuch as the base of the inverted channel is apertured, it follows that the oil vapors are discharged from the channel into the lateral air stream flowing from the flame spreader body and are thereby fed to the flame at points spaced above the wick. As a result, more complete combustion control is effected and the efficiency of the burner is increased.

In addition to the foregoing, the present invention contemplates a burner construction offering the possibility of supporting the burner in a cabinet or the like without the danger of the resulting increase in temperature causing

the flame to creep to such an extent that excessive smoking of the burner results. In accordance with the present invention, the foregoing is accomplished by associating a shield with the burner collar in such a manner that the shield cooperates with the collar to form a space around the outer burner tube for the circulation of air. The air circulating in heat conducting relation with the outer burner tube maintains the same at a sufficiently low temperature to prevent creeping of the flame, irrespective of whether the burner is located in a cabinet or the like.

The foregoing, as well as other objects, will be made more apparent as this description proceeds, especially when considered in connection with the accompanying drawing, wherein:

Figure 1 is a longitudinal sectional view through an oil burner of the wick type embodying the various features of the present invention;

Figure 2 is a fragmentary sectional view showing the flame spreader in its inverted position where it operates to loosen or break the carbon deposits on the upper end of the wick;

Figure 3 is a top plan view of the burner shown in Figure 1;

Figure 4 is a sectional view taken substantially on the plane indicated by the line 4—4 of Figure 3.

Upon reference to Figure 1, it will be noted that my improved oil burner comprises a tubular wick 10 adjustably supported in an oil reservoir 11 formed by inner and outer wick tubes 12 and 13, respectively. The normal oil level is indicated in Figure 1 by the dot and dash line 14 and the interior of the reservoir communicates with a source of supply (not shown) through the medium of a conduit 50. It will also be noted that the outer wick tube 13 is formed with an aperture 16 through one side thereof to provide sufficient clearance for the teeth of the pinion 17 to intermesh with the usual wick carriage 18 for adjusting the wick relative to the wick tubes. The pinion 17 is operated in any suitable manner (not shown herein) and is enclosed by a housing 19 having the inner ends of the side walls crimped around the marginal edges of the opening 16 in a manner to provide an effective seal.

The upper end of the inner wick tube 12 is shown in Figure 1 as terminating short of the corresponding outer end of the wick tube 13 and the adjacent end of the wick is tapered in the manner illustrated so that the top surface of the wick extends from the upper end of one of the

wick tubes to the upper end of the other wick tube. It will also be observed from Figure 1 that the upper end of the inner wick tube 12 is offset radially outwardly to provide an annular 5 shoulder 20 forming a seat for an air baffle channel 21. The air baffle channel 21 is in the form of an inverted channel-shaped ring having the extremity of the outer flange 22 offset radially outwardly to telescopically engage the inner 10 surface of the enlarged end of the wick tube 12 and adapted to seat on the shoulder 20. The base 23 of the channel is tapered in a direction opposite the direction of inclination of the upper end of the wick and is provided with circumferentially spaced apertures 24 therethrough to direct air flowing upwardly in the direction of the arrows A against the flame emitted from the top of the wick. It will also be noted that the flange 22 is provided with a series of circumferentially spaced openings 25 to permit a certain amount of the air to escape from the channel 21 into the space existing between the flange 22 and adjacent end of the inner wick tube 12. The air flowing through the apertures 25 is directed 20 by the upper end of the inner wick tube 12 against the flame at an elevation slightly below the air discharged from the apertures 24 and thereby cooperates with the latter apertures to supply the flame adjacent its source with the 30 amount of air necessary for efficient combustion.

Supported within the inner wick tube 12 is a flame spreader 26 having a tubular body portion 27 extending into the upper end of the inner wick tube 12 and seated at the lower end thereof on a web 28 fixed in any suitable manner to the inner wick tube 12 intermediate the ends of the latter. The tubular body portion 27 of the flame spreader is closed at its upper end and is upset to provide an annular downwardly opening chamber 29 having circumferentially spaced perforations 30 in the top thereof cooperating with perforations 31 in the annular side wall of the body to permit air passing through the flame spreader into the annular chamber 29 to escape. In this connection, it will be noted that the top wall 32 of the body portion is shaped to direct the air flowing upwardly into the body portion 27 outwardly toward the perforations, and this wall is centrally apertured to receive a fastener element 33. The fastener element 33 is in the form of a stud having the lower end riveted or otherwise permanently secured to the web 28 and having the upper end threaded for receiving a nut 34 adapted to prevent accidental disengagement of the flame spreader from the burner. It will be noted from the above that air directed outwardly through the perforations 30 and 31 supplies oxygen to the upper regions of the flame emitted by the wick to insure proper combustion. It will also be noted that the diameter of the body portion 27 is less than the diameter of the inner flange 35 of the air baffle channel so that air is permitted to flow through the resulting space. In order to direct this air outwardly against the flame at an elevation between the air discharged from the air baffle channel 21 and the perforations 31, I provide a flame spreader flange 36. The flange is permanently secured in any suitable manner to the flame spreader body 27 below the perforations 31 and extends radially outwardly from the body in spaced relation to the upper ends of the wick tubes. As a result, the flange 36 forms a baffle for directing air flowing upwardly through the space between the flame spreader body 27 and flange 36 of the channel

21 to direct this air outwardly against the flame.

As shown in Figure 1, the flange 36 is fashioned to provide an annular upwardly projecting downwardly opening channel 37 spaced radially outwardly from the flame spreader body 27 and having perforations 38 in the base portion thereof to permit air entering the channel to escape. The air escaping through the perforations 38 in the base of the channel 37 is directed laterally outwardly against the flame by the air flowing 10 out of the flame spreader body 27 through the perforations 31.

It has been found in actual practice that the above construction eliminates the accumulation of unburned oil on the inner surface of the wick tube 12, and this is probably due to the fact that the draft caused by the air passing upwardly through the inverted channel 21 on the flame spreader flange 36 carries any unburned oil vapors along with it. Inasmuch as the air discharged from the perforations 31 flows across the base of the channel 37, it necessarily follows that the vapors discharged from the perforations 38 are carried outwardly into the flame and are thereby prevented from accumulating on any part 25 of the burner.

After continued use of a burner of the tube previously described, it is necessary to remove the carbon deposits on the upper end of the wick in order to obtain continued efficient operation of the burner. In accordance with the present invention, the carbon deposited upon the upper end of the wick may be quickly loosened or broken down by employing the flame spreader 26 in the inverted position shown in Figure 2. As will be observed from this latter figure, when it is desired to loosen or break the carbon deposit on the upper end of the wick, the nut 34 is removed from the stud 33 and the flame spreader 26 is lifted off the burner. When this is accomplished, the air baffle channel 21 is removed from the inner wick tube 12 and the flame spreader 26 is re-assembled with the burner in an inverted position. In this connection, it will be noted that the portion 40 of the flame spreader flange extending beyond the channel 37 is tapered to such an extent that it engages the tapered upper end of the wick 10 throughout the area of this end of the wick. In other words, the flange 40 rests or seats upon the tapered upper end of the wick and is preferably provided with a plurality of serrations 41 on the top surface thereof to assist in breaking the carbon deposit on the wick upon rotation of the inverted flame spreader relative to the wick. The depth of the serrations is merely sufficient to effect the desired breaking action on the carbon deposit and care is taken to design the serrations so that they will not cut or unravel the wick.

It will also be observed from Figure 2 that the flame spreader is accurately centered in its inverted position with respect to the inner wick tube 12 so that the portion 40 of the flange will seat properly on the tapered upper end of the wick. In the present instance, the radially outer flange of the channel 37 is fashioned to approximately the diameter of the enlarged upper end of the inner wick tube 12 and, as a consequence, telescopically engages the inner surface of the wick tube 12 to effect the desired centering operation. It follows from the above that the flame spreader not only functions to advantageously distribute the air to effect control of the combustion but, in addition, is capable of being used 75

to loosen or break the carbon deposited on the upper end of the wick.

In manufacturing certain types of oil burner stoves, it is necessary to support the burner in a cabinet and difficulty has been encountered with designs of this character to maintain the cooling necessary to prevent the flame from creeping in response to the increase in temperatures resulting from enclosing the burner. In the present instance, provision is made for circulating air in heat conducting relation to the outer wick tube 13 so as to maintain the temperature of the burner sufficiently low to prevent undue creeping of the flame.

In detail, an annular shield 42 is provided having a diameter considerably greater than the diameter of the outer wick tube to provide an annular vertical passage 43 for air, and the upper end of the shield is bent inwardly to form a shoulder 44 adapted to seat on the usual burner collar 45. In accordance with conventional practice, the burner collar 45 surrounds the upper end of the outer wick tube 13 in spaced relation to the latter and is secured in place by means of the brackets 46. It follows from the above that the shield 42 cooperates with the burner collar to form an air passage around the outer wick tube 13 through which air circulates from the lower end of the burner to the upper end of the latter. This circulation of air in heat conducting relation to the burner tube 13 maintains the temperatures sufficiently low to prevent creeping of the flame even in cases where the burner is mounted in a cabinet.

What I claim as my invention is:

1. In a wick type burner, a wick, a flame spreader attachable to the burner in either of two positions, one position being inverted with respect to the other, and means effective in the inverted position of the flame spreader to engage the adjacent end of the wick and effect a rubbing action on said wick upon relative rotation of the flame spreader and burner.

2. In a wick type burner, a wick, a flame spreader attachable to the burner in either of two positions, one position being inverted with respect to the other, a flange on said flame spreader effective in the said other position of the flame spreader to direct air laterally outwardly and effective in the inverted position of the flame spreader to rest on the adjacent end of the wick, and means supporting the flame spreader in said inverted position for rotation relative to the burner to cause said flange to have a rubbing action on said wick.

3. In a wick type burner, an annular wick, a flame spreader attachable to the burner in either of two positions, one position being inverted with respect to the other, an annular flange on said flame spreader effective in the said other position to direct air laterally outwardly toward the wick and effective in the inverted position of the flame spreader to seat on the adjacent end of the wick, serrations extending radially 60 of the flange in circumferential spaced relationship, and means supporting the flame spreader in the inverted position thereof for rotation relative to the burner.

4. In a wick type burner, an annular wick, a wick tube located within the wick, a flame spreader attachable to the burner in either of two positions, one position being inverted with respect to the other, an annular flange on said flame spreader effective in the said other position to direct air flowing upwardly through the

wick tube laterally outwardly toward the wick and effective in the inverted position of the flame spreader to seat on the adjacent end of the wick, means on said flange cooperating with the wick tube to center the flame spreader with respect to the wick in the inverted position of the flame spreader, and means supporting the flame spreader in the inverted position thereof for rotation relative to the burner.

5. In a wick type burner, an annular wick, a wick tube located within the wick, a flame spreader attachable to the burner in either of two positions, one position being inverted with respect to the other, an annular flange on said flame spreader effective in the said other position to direct air flowing upwardly through the wick tube laterally outwardly toward the wick and effective in the inverted position of the flame spreader to seat on the adjacent end of the wick, said flange having an annular channel-shaped portion opening downwardly in the said other position of the flame spreader to receive air passing upwardly through the wick tube and having one of the side flanges telescopically engaging the upper end of the wick tube in the inverted position of the flame spreader to center the latter with respect to the wick, and means supporting the flame spreader in the inverted position thereof for rotation relative to the burner.

6. In a wick type burner, an annular wick, a wick tube located within the wick, a flame spreader attachable to the burner in either of two positions, one position being inverted with respect to the other, an annular flange on said flame spreader effective in the said other position to direct air flowing upwardly through the wick tube laterally outwardly toward the wick and effective in the inverted position of the flame spreader to seat on the adjacent end of the wick, said flange having an annular channel-shaped portion opening downwardly in the said other position of the flame spreader to receive air passing upwardly through the wick tube and having perforations in the base portion to permit escape of the air, the radially outer flange of the channel telescopically engaging in the upper end of the wick tube in the inverted position of the flame spreader to center the latter relative to the wick, and means supporting the flame spreader in the inverted position thereof for rotation relative to the burner.

7. In a wick type burner, an annular wick, a flame spreader attachable to the burner in either of two positions, one position being inverted with respect to the other, and an annular flange projecting laterally outwardly from the flame spreader and having a portion adapted to rest on the adjacent end of the wick in the inverted position of the flame spreader to effect a rubbing action on the wick upon relative rotation of the wick and flame spreader.

8. In a wick type burner, an annular wick having a tapered upper end, a flame spreader attachable to the burner in either of two positions, one position being inverted with respect to the other, and an annular flange projecting laterally outwardly from the flame spreader and having a tapered portion adapted to seat on the tapered end of the wick in the inverted position of the flame spreader to effect a rubbing action on said end of the wick upon relative rotation of the wick and flame spreader.

9. In a wick type burner, an annular wick, a flame spreader having a tubular body extend-

- ing into the upper end of the wick and having a diameter less than the internal diameter of the wick providing an annular passage for air around the flame spreader body, an annular flange extending radially outwardly from the body above the wick to direct air passing upwardly through said annular passage laterally outwardly, said flange having a downwardly opening annular channel-shaped portion located substantially opposite the upper end of the wick 5 to receive unburned vapor and particles of fuel carried by the air passing upwardly through said passage and having the base portion of the channel perforated to permit the escape of the air and fuel particles entering said channel.
- 10 15. 10. In a wick type burner, an annular wick, a flame spreader having a tubular body extending into the upper end of the wick and having a diameter less than the internal diameter of the wick providing an annular passage for air 20

around the flame spreader body, an annular flange extending radially outwardly from the body above the wick to direct air passing upwardly through said annular passage laterally outwardly, said flange having a downwardly opening annular channel-shaped portion located substantially opposite the upper end of the wick to receive unburned vapor and particles of fuel carried by the air passing upwardly through said passage, the base portion of the channel being 10 perforated to permit the escape of the air and fuel particles entering said channel and the portion of the flame spreader body above the flange having perforations for directing air flowing upwardly through the body laterally outwardly in 15 directions transverse to the flow of fluid from the perforations in the base of the channel to direct the air and fuel particles outwardly toward the flame emitting from the wick.
